[57] CLAIM

The ornamental design for a fish bait keeping container, substantially as shown and described.

DESCRIPTION

FIG. 1 is an exploded perspective view illustrating a fish bait keeping container in accordance with my new design showing the interior support tray and cover disposed above their normal mating positions; FIG. 2 is a side elevational view thereof with the top shown raised above its mating position, the opposite side being a mirror image thereof; FIG. 3 is an end elevational view, the opposite end being a mirror image thereof; and FIG. 4 is a top plan view thereof with the cover removed and the interior support tray in place.
